UNITED STATES PATENT OFFICE

155,530

DESIGN FOR A TEXTILE FABRIC

Ruth Montrose, New York, N. Y.

Application November 6, 1948, Serial No. 149,491

Term of patent 3½ years

(Cl. D92—1)

To all whom it may concern:

Be it known that I, Ruth Montrose, a citizen of the United States of America, residing at the city of New York, New York county, New York, have invented a new, original, and ornamental Design for a Textile Fabric, of which the following is a specification, reference being had to the accompanying drawing forming part hereof wherein:

The figure is a plan view of a piece of textile fabric showing my new design.

I claim:

The ornamental design for a textile fabric, as shown.

RUTH MONTROSE.
